UNITED STATES PATENT OFFICE.

JOHN C. JEWETT, OF BUFFALO, NEW YORK.

DESIGN FOR BIRD-CAGES.

Specification forming part of Design No. **11,446**, dated September 30, 1879; application filed July 22, 1879.
[Term of patent 7 years.]

To all whom it may concern:

Be it known that I, JOHN C. JEWETT, of Buffalo, in the county of Erie and State of New York, have originated and designed a Bird-Cage, of which the following is a full, clear, and exact description, reference being had to the accompanying drawing, making part of this specification.

The nature of my design is fully represented in the accompanying illustration, which is an elevation of my newly-designed bird-cage.

A is the base, and B the stand. To the base is affixed a perforated cylindrical part, C, having an outwardly-projecting flange or rim, D, upon which the dome E is fastened.

The relative proportions of the parts are such that the cylindrical part C is of less diameter than the bottom A, and the dome E larger than

said cylindrical part, whereby a bird-cage of unique design is produced.

Having thus fully described my invention, I claim as new—

As a design for a bird-cage shown, consisting of the circular bottom A, the cylindrical reduced perforated portion C, the projecting flange D, and the circular dome E, substantially as described, and shown in the accompanying drawing.

In testimony that I claim the foregoing as my invention I have hereto set my hand and affixed my seal in the presence of two subscribing witnesses.

JNO. C. JEWETT. [L. S.]
